UNITED STATES PATENT OFFICE.

ANTHONY C. BRAMMER, OF WICHITA, KANSAS, ASSIGNOR OF ONE-THIRD TO J. T. McINNES AND ONE-THIRD TO J. J. FITZPATRICK, BOTH OF TULSA, OKLAHOMA.

OIL-WELL DEVICE.

Application filed July 21, 1927. Serial No. 207,534.

This invention relates to oil well devices, and more particularly to a combined tubing support, packing and oil saving device.

It is the common practice to lower a string 5 of tubing into an oil well until it reaches the bottom of the well, and then to elevate the tubing a desired distance and secure it in position, the well being ready to flow oil in the tubing by its natural gas pressure or 10 by applying outside pressure either in the tubing or well casing as desired. The devices ordinarily employed for securing the tubing against downward movement in the desired position are unsatisfactory and 15 numerous devices have been proposed for overcoming the usual difficulties. Such devices, however, are open to several objections, namely, they are usually complicated and expensive to manufacture, and they do 20 not properly seal the tube to prevent oil from leaking past the outside of the tube.

An important object of the present invention is to provide a simple and inexpensive device which is adapted to effectually support 25 the well tubing in the desired position regardless of its length and weight, without danger of breaking the tubing.

A further object is to provide novel packing means surrounding the tubing to prevent 30 leakage past the tubing.

A further object is to provide novel means for compressing the packing to prevent the leakage referred to.

A further object is to provide a novel 35 form of packing member and associated elements whereby the efficiency of the packing is greatly increased.

A further object is to provide a pair of relatively movable members between which 40 the packing element is arranged, and to provide novel take-up means for moving the relatively movable members toward each other to compress the packing.

A further object is to provide novel 45 mounting means for the packing to prevent it from becoming displaced.

Other objects and advantages of the invention will become apparent during the course of the following description.

50 In the drawings I have shown several embodiments of the invention. In this showing:—

Figure 1 is a central vertical sectional view through one form of the device,

Figure 2 is a transverse sectional view on 55 line 2—2 of Figure 1,

Figure 3 is a plan view of the device showing the tubing in position,

Figure 4 is a detail sectional view of one 60 form of packing element,

Figure 5 is a central vertical sectional view of the modified form of the device,

Figure 6 is a plan view of the same, the tubing being shown in section, and,

Figure 7 is a detail perspective of a pack- 65 ing ring.

Referring to the drawings, the numeral 10 designates the body of the device which is provided at its lower end with a base 11 adapted to be received in the ordinary casing head and to be secured thereto in the usual manner. The body 10 is provided with a vertically extending substantially tubular portion 12 which is externally threaded as at 13 for a purpose to be described. The 70 upstanding portion 12 is provided with a plurality of recesses 14 having downwardly converging inner walls as clearly shown in Figure 1. The device may be provided with any desired number of the recesses 14, and 80 in the present instance I have illustrated four of these recesses. The upper end of the upstanding portion of the body is provided with an annular recess 15 for a purpose to be described. The body 10 is pro- 85 vided throughout its length with an axial opening 16 through which the well tubing 17 extends, the tubing being materially smaller in diameter than the opening 16, as shown.

A housing 18 is arranged at the upper end 90 of the body and is provided with a depending annular sleeve portion 19 the lower end of which loosely receives the upper end of the body and is adapted to partake of vertical movement with respect thereto. The upper end of the housing is provided with a conical recess 20 which decreases in diameter 95 toward its lower end. If desired, the housing may be provided with cut out portions 21 to lighten its weight. The lower end 22 of the conical portion of the housing is substantially equal in internal diameter to the diameter of the opening 16, and outwardly of this portion of the housing, the latter is provided with an annular recess 23 arranged 100 in vertical alinement with the recess 15. Slips 24 are arranged within the conical recess 20 as shown in Figure 1. I have il-

lustrated three of the slips in Figure 3 of the drawings, but it will be apparent that any desired number may be employed. The outer faces 25 of the slips are conical and are adapted to engage the wall of the conical recess 20 and it will be apparent that downward movement of the slips causes them to move inwardly toward the well tubing. The inner surfaces of the slips are provided with teeth 26 adapted to engage the tubing to prevent downward movement thereof. Each slip is provided with an ear 27 to which is pivotally connected a handle 28.

15 Referring to Figures 1 and 4 of the drawings the numeral 29 designates a packing member which is preferably formed of an oil resisting rubber composition. The packing member is substantially cylindrical and is adapted to be mounted within the sleeve 19, as shown in Figure 1. The upper and lower ends of the packing member are provided with annular flanges 30 which are adapted to be received in the recesses 15 and 23. The packing member is provided with an axial opening 31 which is substantially equal in diameter to the tubing, and annular grooves 32 communicate with this opening whereby each packing element comprises in effect a plurality of rings which are adapted to contact with the tubing 17 for a purpose to be described.

As previously stated, the body 10 and housing 18 are adapted to partake of vertical movement with respect to each other and this movement is accomplished and utilized for the purpose of properly compressing the packing element 29. As shown, a plurality of screws 33 are threaded in the lower end 40 of the sleeve 19, and the screws correspond in position to and are adapted to have their inner ends engage within the recesses 14. A collar 34 is threaded on the upstanding portion 12 of the body and the upper face 45 of the collar is adapted to engage against the lower end of the sleeve 19. The collar 34 may be provided with outstanding lugs 35 adapted to be engaged by a spanner wrench or similar tool whereby the collar 50 may be rotated.

55 In Figures 5, 6 and 7 of the drawings I have shown a somewhat modified form of the device. Referring to these figures, the numeral 36 designates the body of the device provided at its lower end with an outstanding base 37 which is adapted to be secured in the casing head as will be apparent. The body of the device is provided with an upstanding substantially cylindrical portion 38 the outer face of which is provided with a plurality of recesses 39 the inner walls of which converge downwardly similar to the inner walls of the recesses 14. A housing 40 is arranged over the body of the device, 60 the housing being provided with depending

sleeves 41 slidably receiving the upper end of the upstanding portion 38 of the base. Screws 42, similar to the screws 33, are threaded in the sleeve 41 and have their inner ends engaging within the recesses 39. 70 The upper end of the housing 40 also is provided with a conical recess 43 in which a plurality of slips 44 are arranged. I prefer to employ three of the slips 44, as shown in Figure 6. Handles 45 similar to the handles 75 28, are secured to the slips.

A split packing element 46, preferably formed of an oil resisting rubber composition is mounted within the sleeve 40 and has its lower face supported upon the upper end of the body of the device. A split metallic packing ring 47 rests upon the upper face of the packing element 46 and is provided with an upstanding annular flange 48 arranged in an annular recess 49 formed 85 in the housing 40.

The operation of the form of the device shown in Figures 1 to 4 inclusive is as follows:

The tubing is lowered into the well in the usual manner, and the slips are adapted to support the tubing when it is desired to attach additional tubing sections by means of the usual sleeves. The slips 24 are lowered into position by their handles 28 until the teeth 26 engage the well tubing. It will be obvious that the teeth will efficiently support the tubing and any tendency of the latter to slide downwardly causes the slips to move inwardly to tighten their grip upon the tubing, due to the contacting conical faces of the slips and the recess 20. If it is desired to use the packing 29 as a permanent packing, the screws 33 are turned inwardly and their engagement with the inclined faces of the recesses 14 causes the body of the device and the housing to move toward each other relatively, thus compressing the packing element. It will be apparent that the annular recesses 32 greatly increase the resiliency of the packing member, and with the slips elevated and tension removed from the packing member, the tubing and the sleeve joints thereon may be lowered further into the well as additional tubing sections are attached. 110

115 The resiliency provided by the annular recesses 32 permits the connecting sleeves of the tubing readily to pass through the packing. It has been found that the arrangement of the flanges 30 of the packing element in the annular recesses 15 and 23 causes the packing element to be firmly held against dislodgment. After the packing element has been suitably compressed, the collar 34 is rotated until it firmly engages 120 the lower end of the sleeve 19. This collar then serves to prevent any relative movement, either vertically or laterally, between the body of the device and the housing and accordingly it will be apparent that the ele- 125 130

ments of the device will be securely held in their desired positions. Instead of the packing 29, the packing 46 and metal ring 48 illustrated in Figure 5 may be employed as permanent packing means. The packing 29, in such case, will be employed until the tubing has been lowered to the desired depth in order that the connecting sleeves may pass through the packing. This is particularly important in connection with flowing wells since the packing 29 prevents leakage of oil past the tubing while it is being lowered in position. After the tubing has reached the desired depth, however, the packing 29 may be replaced with the packing and retaining ring shown in Figure 5, these elements serving as permanent packing for the tubing.

The operation of the form of the device illustrated in Figures 5, 6 and 7 is substantially the same as in the form of the device just described, except that the collar 34 and its functions are omitted. This form of the device may be manufactured more cheaply than the form previously described, but has been found to be efficient in operation in connection with wells which do not flow at the casing head. The rings 46 and 47 are omitted until the tubing is lowered to the desired depth, whereupon the rings referred to are placed in position. These rings are split as previously stated, and readily may be placed in position. After the elements are thus assembled the screws 42 are adapted to be moved inwardly to effect compression of the packing element in the manner already described, and obviously the tension on the packing element may be adjusted in either form of the device by proper operation of the screws 33 or 42. The packing ring 47, being provided with the flange 48 arranged within the recess 49, is adapted to secure the packing element against dislodgment.

In either form of the device, the slips are adapted to firmly secure the string of tubing sections in position regardless of their length and weight, without damaging the tubing or causing it to break. With the novel forms of packing elements described, it has been found that an efficient seal is provided around the tubing to prevent the leakage of oil.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. A device of the character described comprising a body portion having an upstanding portion provided with downwardly converging walls, a housing arranged over said body portion, packing means arranged between said housing and said body portion, means carried by said housing and adapted to engage said inclined walls to move said housing and said body portion toward each other to compress said packing means, said upstanding portion being externally threaded, and a collar threaded thereon and adapted to engage the lower end of said housing.

2. A device of the character described comprising a body portion including an upstanding portion having an annular recess in its upper end, the outer face of said upstanding portion being provided with a plurality of recesses, the inner walls of which converge downwardly, a housing arranged over said body and provided with an annular recess arranged in alinement with said first named annular recess, said housing being further provided with a depending sleeve portion, a packing ring arranged between said housing and said body portion and provided with annular flanges arranged in said annular recesses, said ring having an axial opening therethrough, the walls of which are adapted to contract with a well tubing and are provided with annular grooves, a plurality of radial screws carried by the lower end of said sleeve and having their inner ends adapted to engage the converging walls of said second named recesses, slips carried by said housing and adapted to grip against the well tubing, said upstanding portion being externally threaded, and a collar threaded thereon and adapted to engage the lower end of said sleeve.

In testimony whereof I affix my signature.

ANTHONY C. BRAMMER.
